UNITED STATES PATENT OFFICE.

CLARENCE E. MEHLHOPE, OF WINNETKA, ILLINOIS, ASSIGNOR, BY MESNE ASSIGNMENTS, TO UNITED STATES GYPSUM COMPANY.

PLASTER BOARD.

Application filed May 28, 1921. Serial No. 473,288.

This invention relates to plaster board and has in view the production of a strong, tenacious and homogeneous form of plaster board or the like.

5 Among other objects, the invention is intended to supply a form of plaster board in which the top, bottom and edge faces are strongly protected by a substantially continuous covering, while leaving the body, of 10 plaster or similar material, homogeneous and without material points of weakness.

One illustrative embodiment of the invention is shown in the drawings, in which Fig. 1, drawn on a small scale, is a top face view 15 of a strip of plaster board; and Fig. 2 drawn on a larger scale, is a transverse section on the line 2, 2 of Fig. 1.

Fig. 2 shows the body 3 of plaster or the like having on one face a cover sheet 4 preferably of fibrous material such as heavy paper, and having a cover sheet 5 of like material on the other face. The cover sheets 4 and 5 are so associated that collectively they supply a practically continuous envelope encircling the top, bottom and edge faces of the plaster body. For instance, in the illustrative form the cover sheet 4 is folded over the body edges, and the margins 6 overlie the top face of the plaster 25 body; the top cover sheet 5 is applied to the top face of the plaster body, and interposed between the edges of the bottom-sheet margins 6, 6. As shown, the sheets 4 and 30 5 do not overlap in any sense. On the contrary, their adjacent edges, wherever located, are preferably butt-jointed as nearly as practicable in ordinary commercial operations, so as to render the enveloping of the plaster body by the cover sheets, as 35 40 completely continuous as desired.

Whatever joints occur between the edges of the cover sheets are effectually sealed by sealing strips 7, 7 formed of thin and tough material overlapping and securely cemented 45 to the adjacent cover sheet margins at each joint. For example, after the cover sheets are assembled with the plaster body, gummed paper strips, of thin tough character may be pasted over the joints to seal them 50 and, in effect, to establish a substantially integral and continuous encircling envelope. The material of the sealing strips is pre-

ferred to be of a tensile strength equal to or greater than that of the cover material in the sheets 4 and 5.

55 Referring to Fig. 2, the sheets 5 and 6 practically merge into each other and are strongly sealed together by the glued or cemented strips 7, which are adhered to the covering sheets independently of the plaster 60 body. The sealing strips 7, 7 being secured in place by a glue or cement of the highest efficiency, the sealing strip is in effect, an integral part of each covering-sheet margin to which it is attached, and hence those margins function as though they were integral with each other. At the same time, the sealing strips 7, although very tough and strong, are so thin, and are so securely glued in place, that the opportunity to tear or pry 65 up their edges is minimized.

70 The illustrative plaster board may be made in any appropriate manner. For instance, a bottom cover sheet may be fed past a chute which delivers plaster on the upper 75 face thereof, after which the margins of the bottom sheet may be progressively folded upwardly and inwardly to embrace the edges of the plaster body; thereafter the top sheet 5 may be applied in position between the 80 edges of the inturned margins of the bottom sheet. The substantially continuous envelope of cover sheet having been applied, the sealing strips may be glued or cemented in place preferably after the plaster body has 85 set sufficiently to afford adequate resistance to such pressure as may be exerted upon the sealing strips to cause them to adhere strongly to the cover sheets.

90 As will appear to those skilled in the art, this invention is applicable to composite boards and the like made of materials which are functionally equivalent to but are specifically different from the plaster and paper referred to above. Such other materials, 95 where suitable for substantially stiff and rigid wall boards, and the like, are intended to be included within the subjoined claims.

I claim:

1. A composite board comprising, in combination, a plaster body; substantially continuous fibrous cover material enveloping the body; and relatively thin, tough sheet material and an adhesive substantially 100

stronger than said plaster for sealing portions of said covering material together to complete its continuity.

2. A composite board or the like comprising, in combination, a plaster body; a bottom cover sheet having its margins folded over the body edges and inturned onto the top face of the body; a top covering sheet interposed between the edges of the inturned margins of the bottom sheet and lying in substantially the same plane therewith; and means for sealing said margins together independently of the plaster of the body.
3. A composite board or the like comprising, in combination, a plaster body; a bottom cover sheet folded over the body edges and onto the top surface of the body; a top cover sheet lying wholly between the inturned mar-

gins of the bottom sheet; and relatively thin, tough sealing strips glued or cemented to the 20 respective covering-sheet margins to seal them together.

4. A composite board or the like comprising, in combination, a substantially rigid plaster body; a bottom cover sheet applied 25 to one face of the body; a top cover sheet applied to the opposite face of the body, said sheets having their edges contiguous but not overlapping; and relatively thin sealing strips, of tensile strength at least equal to 30 that of the cover sheet material, sealing together the contiguous edges of the cover sheets.

In testimony whereof, I have signed my name to this specification.

CLARENCE E. MEHLHOPE.
